UNITED STATES PATENT OFFICE.

JESSE KERN, OF HAMLIN, KANSAS.

DESIGN FOR A BUGGY-BODY.

44,446.

Specification for Design.

Patented Aug. 5, 1913.

Application filed March 29, 1913. Serial No. 757,708. Term of patent 7 years.

To all whom it may concern:

Be it known that I, JESSE KERN, a citizen of the United States, residing at Hamlin, in the county of Brown and State of Kansas, have invented a new, original, and ornamental Design for Buggy-Bodies, of which the following is a specification, reference being had to the accompanying drawing, forming part thereof.

The figure is a perspective view of a buggy body, showing my new design.

I claim:

The ornamental design for a buggy body, as shown.

JESSE KERN.

Witnesses:

EZRA LATHLY,
J. C. FUGER.
